UNITED STATES PATENT OFFICE.

MILTON H. KNAPP, OF ADRIAN, MICHIGAN.

BLOW-PIPE.

SPECIFICATION forming part of Letters Patent No. 244,623, dated July 19, 1881.

Application filed May 4, 1881. (No model.)

To all whom it may concern:

Be it known that I, MILTON H. KNAPP, of Adrian, in the county of Lenawee and State of Michigan, have invented new and useful Improvements in Blow-Pipes, of which the following is a specification.

The nature of my invention relates to certain new and useful improvements in blow-pipes, such as are usually employed by dentists and jewelers, by means of which various adjustments are obtained which will be found of great practical utility, and by which various sizes of flame and intensity of the same can be had, or compound flames can be produced, as the varying conditions of the work in hand may render desirable.

The invention consists in the peculiar construction of the parts and their various combinations, as more fully hereinafter described.

Figure 1 is an elevation of my improved compound blow-pipe, partially in section. Fig. 2 is a detached perspective of the stand with the crotched or forked blow-pipe attached. Fig. 3 is a central section of the burner attached to the standard by the universal joint.

In the accompanying drawings, which form a part of this specification, A is a metal base, of proper size and weight to give a firm and steady support to the parts attached thereto.

B is a hollow arm or tube, which projects horizontally from this base, and is provided with the stop-cock C. The tube B communicates with the vertical tube D, which contains a jet-tip, E. The tube-burner F, which is screwed 35 upon the tube D, contains air-inlets a, slightly above the tip E, and serves also as support to the crucible-holder G.

H is an air-blast tube adjustably secured to the base A by the screw b passing through the 40 slotted plate c. The upper end of the tube H is bifurcated, as shown in Fig. 2, the bifurcations leading up on opposite sides of the tube F and terminate in two jet-tips, d d.

The hollow arm or tube B serves as a support to the hollow standard I, which is adjustably secured thereon by a set-screw, e. J is another standard, adjustably secured in the hollow standard I by means of a set-screw, f.

K is a gas-tube, which joins the standard J 50 at g, from which point up the standard J is also

hollow, and forms a continuation for the tube K, and is provided with the stop-cock L, and swivel M, connecting the standard J with the pipe N. The pipe N, which is shown in Fig. 3 in section, is slipped into the tube-burner P 55 and terminates in a tip, O.

Secured alongside the tube-burner N, and forming a slight angle therewith, is the blast-pipe Q, which enters likewise the tube P and terminates at R. The tube P contains also air-inlets h, and its opening i can, by the adjustments above described, be brought in proximity to a crucible resting upon the holder G, Fig. 1.

S is a tube conveying another air-blast 65 through the jet-tip t to the blow-pipe flame issuing at i. This pipe S is adjustably and removably secured upon the pipe N by means of the lug m and set-screw o, which latter engages in a slot, n, of the lug p secured to the tube N. 70

T is a flexible tube conveying the air-blast through the branch-tubes V, W, and U to the blast-jets before described.

X is a stop-cock in the flexible main tube T, and r another stop-cock in the branch tube W. 75

Z is a flexible tube conveying the gas to the burner F, while a branch tube, Y, provides the burner P.

In practice, the gas being turned on and ignited at the burners, and the crucible containing the material to be operated upon set into the basket G, any desired blow-pipe flame can be obtained by adjusting the blast-tubes S and H by means of the adjustments before described. The blast issuing through the tube 80

H at d d can be obtained in a ring form by lowering the tube H, so as to make the blast impinge against the sides of the burner-tube P before arriving at the flame. By raising the tube H a pointed flame is obtained, as the jets 90 d d are slightly converging. The blast from the blow-pipe S can be directed upon the blow-pipe flame issuing at i at any desired point, so as to concentrate the heat and produce a pointed flame, or a touch of the hand can remove it 95 without disturbing the other adjustments. The pipe N is also entirely under control of the hand, and can be adjusted upon the work or removed without disturbing the other burner.

As the entire effect of the two blow-pipes 100

can be concentrated upon the work a very high degree of heat can be obtained, while at the same time more material can be operated upon with the same ease than with a single blow-pipe.

What I claim as my invention is—

1. The combination of the burner F with a bifurcated blow-pipe, the jets of which slightly converge, and which, by means of a vertical 10 adjustment, will deliver the blast to the flame straight or in a ring form, substantially as described.

2. The combination of the burner P and the blow-pipe Q, delivering a jet into the burner- 15 tube at a point short of the gas-jet delivery, by

which means a larger quantity of mixed gas can be obtained, substantially as described.

3. The combination of the burner P and the inclosed blow-pipe Q with the adjustable blow-pipe S, substantially as set forth.

4. The combination of the burners F, provided with a blow-pipe, H, and the adjustable burner P, provided with the adjustable blow-pipe S, when arranged and constructed substantially as specified.

20 MILTON H. KNAPP.
